(57) **CLAIM**

The ornamental design for a light bar housing with wide opening, as shown and described.

DESCRIPTION

FIG. 1 is a top perspective view of a light bar housing with wide opening;

FIG. 2 is a bottom perspective view thereof;

FIG. 3 is a top elevation view thereof;

FIG. 4 is a left side elevation view thereof, the right side elevation view being a mirror image thereof;

FIG. 5 is a bottom elevation view thereof; and,

FIG. 6 is a front elevation view thereof, the rear elevation view being a mirror image thereof.
